[57] CLAIM

The ornamental design for a cushion with compartment and removable pad, as shown and described.

DESCRIPTION

FIG. 1 is a left side and top perspective view of a cushion with compartment and removable pad showing my new design, the right side being a mirror image of the left;

FIG. 2 is a top and front perspective view thereof;

FIG. 3 is a bottom and front perspective view thereof;

FIG. 4 is a reduced bottom and left side perspective view thereof, showing the compartment opened;

FIG. 5 is a top and left side perspective view thereof, with the pad portion shown removed;

FIG. 6 is a top plan view of the pad portion thereof, the bottom being identical in appearance;

FIG. 7 is a top and left side perspective view of a second embodiment of a cushion with compartment and removable pad showing my new design, the right side being a mirror image of the left;

FIG. 8 is a top and front perspective view thereof;

FIG. 9 is a bottom and front perspective view thereof;

FIG. 10 is a reduced bottom and left side perspective view thereof, showing the compartment opened;

FIG. 11 is a top and left side perspective view thereof, with the pad portion shown removed;

FIG. 12 is a top and front perspective view thereof, with the pad portion shown removed; and,

FIG. 13 is a top plan view of the cushion portion thereof, the bottom being identical in appearance.
